UNITED STATES PATENT OFFICE.

BERTHOLD KUCKUCK, OF WANSEE, NEAR BERLIN, GERMANY, ASSIGNOR TO HÜLSBERG & CIE. MIT BESCHRANKTER HAFTUNG, OF CHARLOTTENBURG, GERMANY, A CORPORATION.

APPARATUS FOR IMPREGNATING WOOD OR OTHER SUBSTANCES.

No. 866,487.

Specification of Letters Patent.

Patented Sept. 17, 1907.

Application filed June 16, 1906. Serial No. 322,095.

To all whom it may concern:

Be it known that I, BERTHOLD KUCKUCK, engineer, a subject of the German Emperor, residing at Wannsee, near Berlin, Germany, have invented certain new and useful Improvements in Apparatus for Impregnating Wood or other Material; and I do hereby declare the following to be a full, clear, and exact description of the invention, such as will enable others skilled in the art to which it appertains to make and use the same.

10 My invention relates to an apparatus for impregnating wood or other material with creosote oils, or other readily inflammable materials, or materials which develop inflammable gases. Hitherto in the case of such impregnation processes the impregnating materials, particularly tar-oil, are forced from the various reservoirs by means of compressed air which had the disadvantage that dangerous explosions could easily occur. In order to avoid this danger the air which is employed is according to the present invention first of all led 20 through a suitable coke-furnace or the like in which, according to the nature of the materials employed for the impregnation process, a certain percentage of the oxygen in the air is converted into carbonic acid gas, so that the formation of explosive mixtures of air and 25 gas is absolutely impossible. The air must of course be cooled before being used and this can be effected by means of special cooling apparatus or by means of long length of tubing or pipes. Further, the several vessels or cylinders are connected with one another in 30 such a way that the air can be used for several working periods. Thus the air, which is poor in oxygen and which has been compressed by the compressor, is first forced under pressure upon the wood, in order that later, after the impregnation with liquid has been effected, it may on expanding expel a part of the impregnating liquid. The same air in the impregnating-vessel is however utilized again in order to displace the liquid from the so-called charging-vessel; finally the air from the charging-vessel is utilized for the third 35 time in order to perform the compressing work proper, a compressor compressing the air to a higher pressure being utilized. For this purpose an arrangement of apparatus is employed such as that shown diagrammatically in the accompanying drawings.

40 The compressor H draws in atmospheric air which before reaching the compressor first passes through a coke furnace K, part of the air passing under the grate and part passing into the combustion space. The relative amounts of the air passing into the coke furnace 45 respectively above and below the grate can be regulated in a suitable manner by means of cocks a and b in such a way that a mixture of gases is obtained which contains a certain percentage of carbonic acid gas and on the other hand is free from carbon monoxid. The gases leaving the coke furnace before entering into the 50 compressor are first led through a cooler J, which if desired may be dispensed with if the tubing from the coke furnace to the compressor is very long and itself provides a sufficient area of cooling surface. The wood or other material to be impregnated is placed in the 55 impregnating-vessel or cylinder A. The impregnating liquid is first introduced into the charging-vessel or cylinder C by forming a vacuum in C; the measuring-vessel or cylinder B is filled with impregnating liquid in the same manner. All the cylinders A, B and C 60 are connected with a common air-pipe M at the top and with a common pipe N for liquid at the bottom. The cocks f, g, h, enable each single one of the three reservoirs to be shut off from the air-pipe M and the cocks p, q, r render it possible for said reservoirs to be 65 shut off from the liquid-pipe N.

It will now be assumed that the whole plant is in the condition represented in the drawings, that is, the cylinder A is charged with wood and the measuring-cylinder B and the charging or feeding-cylinder C are filled 70 with impregnating liquid. The cocks p, q and r are closed, while the cocks f, g, and h are open. The pipe N is bent downward into the tank L, and just above this tank the pipe N is provided with a cock s, which is 75 closed when the cocks p, q and r are closed. The air-outlet cocks of the several cylinders, which cocks are indicated by n, k, and i are closed. The compressor H is now set in action and it draws in air through the coke furnace and forces it into the three cylinders C, B and 80 A. When the desired pressure, for example four atmospheres, has been reached, first the valves e and g are closed. The valves p and r are opened, so that the impregnating material flows from the charging-cylinder C into the impregnating-cylinder A. It will readily be 85 seen that in this case the compressed air present in A is not lost but that in the same measure as the impregnating-cylinder becomes charged with liquid from the cylinder C which is situated at a higher level, the air must flow over from A to C. When now the impregnating-cylinder is charged, the valves p, h and f 90 are closed, whereupon a small compressor D is set in action and draws in the air present in the cylinder C under a pressure of four atmospheres and forces it into the measuring-cylinder B. As soon as the pressure in the latter is greater than that in A the valve q is opened so 95 that during the continued action of the compressor the liquid in the measuring-cylinder B is forced into the impregnating-cylinder A. The pressure is gradually increased for example up to eight atmospheres and the impregnation proper of the wood is effected; the quantity of the material pressed into the wood can be read off in the measuring-cylinder which is fitted with suitable indicating devices. As soon as the wood has taken up 100 105

the desired quantity of impregnating material the valves *m*, *l*, and *q* are closed and the air which may be still present in *C* is allowed to escape through the valve *n*. If the valve *p* is now slowly opened the impregnating liquid must flow back out of the impregnating-cylinder *A* to the charging-cylinder *C*. When the pressure in the impregnating-cylinder has fallen to about $\frac{1}{2}$ to 2 atmospheres compressed air is allowed by opening the valves *g* and *h* to flow into the cylinder *A* from the cylinder *B* which for the greater part is still filled with compressed air at a pressure of 8 atmospheres. By this means it is possible to empty the cylinder *A* entirely or at least until the liquid is at its original height in *C*. After this the valves *p* and *r* are closed and the compressed air is let off from *A* and *B*. After this both of the cylinders *A* and *B* are exhausted by being connected with the vacuum pump *G*. The moisture thus extracted from the wood is deposited in the cooler *E* and the condensed water can be measured in the vessel *F*. The valves *g* and *h* are then closed and atmospheric air is allowed to enter *A*. The impregnating liquid which has collected in the impregnating-cylinder during the exhaustion of said cylinder is drawn off into the cylinder *B* by means of the vacuum in said cylinder and the quantity of liquid absorbed by the wood is made up for by a supply from store-reservoir *L*.

What I claim as my invention and desire to secure by Letters Patent, is:-

1. An apparatus for impregnating wood or similar materials comprising a coke furnace, means for supplying air thereto, a compressor, connections between said compressor and furnace, a vessel for holding the material to be treated, a charging vessel containing the impregnating material, connections between said vessels, and means for conveying compressed gas from said compressor to said charging vessel, substantially as described.
2. An apparatus for impregnating wood or similar materials comprising a coke furnace, means for supplying air thereto, means for cooling the gas as it leaves said furnace, a compressor, connections between said furnace and said compressor, a vessel for holding the material to be impregnated, a charging vessel containing the impregnating material, connections between said vessels, and means for conveying compressed gas from said compressor to said charging vessel, substantially as described.

3. An apparatus for impregnating wood or other material comprising a coke furnace, means for supplying air in regulated amounts thereto, a compressor, connections between said furnace and said compressor, an impregnating vessel, a charging vessel containing impregnating material, connections between said vessels, and means for conveying gas from said compressor to said charging vessel, substantially as described. 50

4. An apparatus for impregnating wood or similar materials, comprising a coke furnace, means for supplying air in regulated amounts to said furnace, means for cooling the gas as it leaves said furnace, a compressor, connections between said compressor and said furnace, an impregnating vessel, a charging vessel containing impregnating material, connections between said vessels, and means for conveying gas from said compressor to said charging vessel, substantially as described. 55

5. An apparatus for impregnating wood or similar materials, comprising a coke furnace, means for supplying air thereto, a compressor, connections between said furnace and said compressor, an impregnating vessel for containing the material to be treated, a measuring vessel, a charging vessel for containing the impregnating material, connections from said compressor to said charging vessel, adjustable means connecting each of said three vessels with said connections, a conductor for the impregnating material, and adjustable means connecting each of said three vessels independently with said conductor, substantially as described. 65

6. An apparatus for impregnating wood or similar materials, comprising a coke furnace, means for supplying air in regulated amounts thereto, a compressor, connections between said compressor and furnace, an impregnating vessel for containing the material to be treated, a measuring vessel, a charging vessel for containing the impregnating material, a pipe conducting the compressed gas from the compressor, adjustable means connecting each of said three vessels independently with said pipe, a conductor for the impregnating material, adjustable means connecting each of said three vessels independently with said conductor, 70

a second gas compressor, adjustable means connecting the suction side of said second compressor with the charging vessel, and adjustable means connecting the delivery side of said compressor with the measuring vessel, substantially as described. 75

In testimony whereof, I have affixed my signature, in presence of two witnesses.

BERTHOLD KUCKUCK.
